DISPLAY STAND

Arthur D. Duncan, Los Angeles, Calif., assignor to Capitol Records, Inc., Hollywood, Calif., a corporation of California

Application September 12, 1950, Serial No. 12,153

Term of patent 7 years

(Cl. D80—10)

To all whom it may concern:

Be it known that I, Arthur D. Duncan, a citizen of the United States, residing at city of Los Angeles, county of Los Angeles, and State of California, have invented a new, original, and ornamental Design for Display Stands, of which the following is a specification, reference being had to the accompanying drawing, forming a part thereof.

Figure 1 is a perspective view of a display stand, embodying my new design with certain of the swinging and arm elements removed to avoid confusion; and

I claim:

The ornamental design for a display stand, as shown and described.

ARTHUR D. DUNCAN.
